UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP CAR.

Application filed February 20, 1925. Serial No. 10,493.

This invention relates to improvements in dump cars.

The object of this invention is to improve the construction of dump cars and extend the usefulness of the same to various kinds of services by providing improved dumping mechanism which will enable the contents of the car to be dumped either centrally of the rails or to the sides thereof as desired. 10 It is also an object of the invention to provide improved construction at the ends of the car which will direct lading to the dumping opening, and thereby extend the dumping length of the car, without increasing the length of door openings intermediate of the tracks, and permit the car to be utilized in services usually performed by flat floor gondola cars, such as hauling lengthy, or other special materials.

20 The invention further consists in the improvements in the parts and devices and in the novel combinations of the parts and devices herein shown, described and claimed.

In the drawings forming a part of this specification, Figure 1 is a broken side elevational view of a portion of a car showing my improvements in connection therewith. Figure 2 is a top plan view of that portion of the car illustrated in Figure 1, the dumping doors in this view being omitted for the purpose of showing the arrangement of the operating mechanism more clearly. Figure 3 is a vertical sectional view through the car on a line corresponding substantially to a line 3—3 of Figure 2, said view showing the dumping doors in center discharging position. Figure 4 is a view taken on a line corresponding substantially to a line 4—4 of Figure 2, said view particularly illustrating the arrangement of the doors and mechanism for side dumping. Figure 5 is a vertical, sectional, partly elevational, view of the end of the car taken on a line slightly to one side of the longitudinal center of the car, and illustrates the end construction of the car. Figure 6 is a fragmentary side elevational view of the end of the car as viewed exteriorly, illustrating the side outlet door at the end of the car.

50 In said drawings, the car is shown as having fixed vertical end walls 9. A—A denote the side walls of the car including side sheets 10, stakes 11, and reinforcing angle shaped bulb members 12 disposed along the lower margin of the side sheets 10 and secured

thereto; B indicates the center sill construction, which in the form shown, comprises a plurality of channels 13—13 and a plate 14 forming a girder-like structure; and C—C denote fixed transversely extending walls adjacent each end of the car, defining the opposite ends of dumping hoppers, each of said walls having a vertical section 15, and sloping portion 16, the upper edge of said sloping section being secured to 60 and supported by a transversely extending beam member 17 connected to the center sill structure, and to the reinforcing marginal bulb members 12 of each of the car side walls. Intermediate the transverse wall 70 sections C the car is provided with a hopper construction, which includes four hoppers D, longitudinally arranged in pairs on each side of the center sill, the hoppers being separated from each other longitudinally 75 of the car by a transversely extending hollow cross-beam structure E. The cross-beam structure E is preferably formed of plate sections 18—18 disposed on opposite sides of the center sill and partly supported by 80 a beam member 19 which extends across the plane of the center sill and is connected thereto and at the side walls of the car. Each section 18 is preferably of inverted V shape presenting inclined walls 20—20 85 which slope away from each other, and include lower vertically depending portions 21, the sections 18 defining the inner end walls of the hopper sections D. As most clearly shown in Figures 2 and 3, each hopper section D includes an outer downwardly and inwardly inclined side hopper sheet 22, secured to the adjacent side wall of the car as indicated at 23 and is suitably braced and rigidified. The opposite side of each 90 hopper section D includes an inner downwardly and outwardly inclined hopper sheet 24, the hopper sheets 24 for all of the hopper sections being preferably in the form of a unitary structure carried by the center sills 100 B and suitably rigidified longitudinally by means of angle members 25 secured to the respective sides of the center sill structure B by means of brackets 26. The remaining portion of each hopper bottom section 105 D is formed by a movable load discharging door or movable floor member E' adapted to assume a substantially horizontal position when in closed position, and adapted to have alternative pivotal and swinging move- 110

ment at its opposite sides so as to permit tilting of the door in either of two desired opposite directions, or to permit of both sides of the door being lowered simultaneously to allow lading to discharge on either side of the door. These features of my invention are in many respects an improvement on my United States Patents Nos. 825,580 and 825,581, dated July 10, 1906. In the constructions covered in these patents, the doors are arranged for operation by mechanism disposed beneath the door, requiring the disposition of the door adjacent the top of the center sill, and necessitating a large opening to clear the center sill when the doors are operated for center dumping. Furthermore, in such an arrangement the height of the door from the rail renders it useless for safe and economical ballasting. I overcome these deficiencies in my present invention by mounting the load discharging floors adjacent the lower portion of the center sill, and disposing the operating mechanism above the doors.

As most clearly seen in Figures 3 and 4, the doors E' are adapted for operation by means of longitudinally disposed shafts 27 and 28 respectively disposed under sloping floor sheets 22 and 24 on both sides of the car, and since the shafts and operating mechanism are similar, the same reference characters will be utilized to designate similar parts of the same. Said shafts are connected with the doors by means of self-locking linkage mechanism F which includes a terminal link 29 having a hook shaped portion 30 adapted to rest over the shaft in the manner hereinafter described and having the lower portion thereof pivotally connected with the door at a point below the floor of the same as hereinafter described. The mechanisms F are preferably disposed at the ends of the door of each hopper section and for this purpose each door section is adequately braced longitudinally by means of beam members 32 preferably in the form of Z-bars. The beam members on the opposite sides of the door are connected by transversely extending stiffening members 33 through the medium of gussets 34, and bracket members 35 are disposed outwardly of the beam 32 to support the overhanging portion of the door. The longitudinal beam members 32 are extending at each end a limited distance beyond the door plate and a bracket 36 is secured to the web and lower flange of the Z-bar 32. Said bracket 36 is provided with a transverse wall 37 through which a pin 38 extends, whereby the link 29 of the door mechanism F is connected with the door. The pin 38 is extended longitudinally of the door and maintained in fixed relation with the bracket by means of a rivet or bolt 39 causing the pin 38 to function in effect as a fixed trunnion. The

bracket 36 is also further braced by a longitudinally extending depending flange 40.

The floors E', as shown, are preferably formed in two groups longitudinally of the car and intermediate said groups a cross shaft 41 is provided which extends to the sides of the car. The shaft 41 is for the purpose of operating the floor doors E' for center dumping, and for this purpose it is operatively connected by means of worms 42, and gears 43, to the shafts 28, it being the preferred construction to open said doors for center dumping in unison as illustrated in Figure 3. The worm and gearing for each shaft 28 is supported in a housing 144 carried by a bracket plate 44 which latter is carried by the center sill and the transverse beam member 19. At the sides of the car each end of the shaft 41 is supported in a bearing 45 which depends from a vertical gusset plate 46 carried by the side of the car, and braced to the sloping floor hopper sheet 22 by means of flanged gussets 47. Any suitable shaft locking and rotating means may be used at the ends of the shaft, but the shaft is preferably locked at each end by means of locking pawls 48 acting on ratchet wheels 49 fixedly mounted on shaft 41, said pawls being operable in unison by means of a transversely extending shaft 50. Outwardly of each said locking ratchet wheel there is provided an operating ratchet 51 with which may be associated a suitable shaft rotating pawl and lever (not here shown).

The arrangement permitting opening of two hopper doors simultaneously provides for a safe and convenient arrangement for ballasting purposes as the lading from the respective hoppers flows towards each other as indicated by the lines 52-52 and thereafter flows from the free edges of the doors toward the rails as indicated at 53-53. Baffle plates 54 at the center of the car and 69 at the ends of the hopper section extend in a transverse vertical plane at the end of each door to prevent an undue flow of material at the ends of the doors.

The preferable arrangement for opening the doors outwardly to discharge at the sides of the car provides for opening one door independently of the other. For this purpose, the shaft 27 is operatively connected by means of worm 55 and gearing 56 with a short transverse shaft 57, which is supported by means of a gusset plate 58. The worm 55 and gearing 56 is disposed adjacent the end of a hopper section and supported in a housing 59 by means of a gusset plate 60 carried by the aforesaid gusset plate 58, and a fixed floor section 61 which extends from the end of the hopper towards the bolster G of the car. The transverse operating shaft 57 carries a locking ratchet 62 with which cooperates a locking pawl 63 adapted

to be locked in position by a cam 64, and outwardly of said locking ratchet 62, there is an operating ratchet 65 with which shaft rotating means (not shown) is adapted to 5 co-operate. Each operating shaft 27 is supported beneath the cross-beam E by means of a bearing 66 carried by a gusset plate 67 supported by the transverse beam 19 and the gusset plate 46, and at the end of the shaft 10 27 remote from the worm and gear, a shaft bearing 68 is provided which is supported from a transverse baffle plate 69. The baffle plates 69 are disposed at the ends of each related hopper section, and extend between 15 the center sill and the side of the car, and are secured to both of said members. At the operating end of the car the worm and gear arrangement constitutes a carrying means for the shaft. The shafts 28 which 20 operate the doors for center opening are supported beneath the cross-beam E by means of the worm and gear housing 144 and at the ends of the shafts by means of shaft bearings 70 which are carried by the transverse 25 baffle plates 69.

As all the arrangements of door operating mechanisms F and related parts are the same, the description of one will suffice. Each of said mechanisms includes a polygonal winding drum 71 fixedly mounted on the shaft in connection with links 72, 73, 74 and the terminal link 29 adapted to wind around said drum, the link 74 having a locking shoulder 174 adapted to engage a locking shoulder 75 on the drum, and the terminal link 29 having a bent end 30 hinged to the link 74 directly over the center of the drum when the mechanism is wound up to its maximum extent. With this arrangement of door operating mechanism, it will be seen that the door E' has a pivotal movement about the pivot 38 independently of the release of the door mechanism and it will be further seen by reference to Figure 4 that 40 as the door is opened the thrust of the load against the door, which is in the direction of the arrow 76, tends to force the terminal link 29 rearwardly against one of the walls of the polygonal drum 71. As the pivot 38 about which the floor pivots is below 45 the level of the door floor, the floor door plate is formed to curve on a radius 138 described with the pivot 38 as a center, and the door is extended somewhat beyond these 50 pivots and also beyond the side walls 22 and 25 of the hopper which serves to eliminate any crack or aperture between the door and the framing when the former is open as well as providing a longer door which serves 55 as an extension to throw the lading further away from the rails, said lengthened door being particularly advantageous to restrict the flow of the material when depositing ballast. The sets of mechanisms F on the 60 opposite ends of each floor E' are adapted 65 to wind in opposite directions in order to secure the floor against lateral or swinging movement.

This arrangement of discharge doors and door operating mechanisms is an extremely 70 convenient and economical one from an operating standpoint as the load may be discharged either centrally of the rails or to the sides of the car without the necessity of converting the cars in a predetermined manner 75 but it is also obvious that the use of releasable door supporting means at the two edges of the doors involves additional expense and additional weight in the doors and mechanism and in order to compensate for such 80 additional weight it is highly important to restrict the length of hopper opening and doors for the same to its smallest dimension while still maintaining the cubical capacity 85 of the car. In this invention I attain this 90 object by increasing the height of the car walls and the dumpable length thereof by having a large load carrying space at the ends of the car. Forming a portion of the level floors at each end of the car over the 95 trucks is a movable member 77 which is preferably hingedly mounted at 78 adjacent the upper edge of the transverse end sloping floor 16 of the hopper portion and adapt the said member 77 for placement in an inclined position as indicated by dotted lines 100 in Figure 5. Such floor is preferably maintained in the inclined position by braces 79 which are pivotally mounted to fixed brackets 80 and may be bolted or otherwise 105 secured to the under-surface of the movable floor as at 81. A subfloor is provided beneath the movable floor section 77 by means of floor plates 61 and 161 and the top of the bolster G being raised somewhat 110 above the plane of the said subfloor forms a support for the movable floor section 77. When the movable floor sections at the respective ends of the car are positioned as 115 portions of a car adapted for service as a level floor car, each of the members 77 rests on the bolster G with the upper surface substantially in alignment with fixed floor sections 82 each of which extends outwardly 120 from the end of the member 77 to the end 115 of the car, thereby giving the advantage and equivalent of a flat floor car for the conveyance of long material, such as lumber, and for this purpose the top of the center ridge and transverse ridge E, which is 125 formed with a narrow flat surface 83^a, are substantially on the same level as the flat floor portions over the truck. When material such as coke which occupies considerably more space for a given weight than the 130 majority of dumpable materials such as stone or coal, the movable floor members 77 may be positioned as forming a portion of the level floor and the major part of lading may then be dumped through the depressed 130

hopper portions D, and for the purpose of facilitating unloading of that portion of the load adjacent the ends of the car a swinging side door 83 is provided in the side wall of the car at each corner adjacent the ladder. It will thus be seen that the car will perform the service of the usual hopper in either center or side dump and be available as a ballast car and also perform the service 10 of a level floor gondola car.

While I have shown and described a specific form of my invention, it will be understood that the same is merely illustrative and I claim all modifications coming within 15 the scope of the claims.

What I claim is:

1. In a dump car, the combination with a longitudinally extending hopper having inwardly and downwardly extending walls, 20 said walls being spaced from each other to define a hopper opening; of a bodily movable door adapted to close said opening and adapted for tilting either right or left; an operating shaft disposed at the opposite end 25 of each door beneath the sloping wall of the hopper; self-locking linkage mechanism connecting each shaft and door, said mechanism including a member extending downwardly from the shaft and pivotally connected with 30 the door, said last named connections constituting the hinge attachments for the door.

2. In a dump car, the combination with a hopper having a discharging opening directly over the rail; of a closure for the 35 discharge opening, said closure being movable to discharge lading to either side of the rail; operating shafts located near the free edges of the closure and above the plane of the same; and links between the respective 40 shafts and doors, each of said links resting above the shaft when the door is in closed position and having a pivotal connection with the closure below the level thereof.

3. In a dump car, the combination with a longitudinal hopper having a dumping opening; of a door extending across the opening; releasable supporting means adapted to support the door adjacent its opposite edges 50 and permit inclination of said door in a plurality of directions, each of said releasable supporting means including a longitudinally extending shaft disposed above the plane of the door and linkage mechanism extending between the door and shaft, said door having a pivotal connection with the linkage mechanism at a level below the plane of the door.

4. In a dump car, the combination with 60 a longitudinal hopper having a dumping opening; of a load discharging floor extending across the opening; a longitudinally extending shaft disposed in parallelism with each edge of the floor and above the same; 65 releasable means adapted to engage the said

floor adjacent its opposite edges and support the same from each of the said shafts and permit inclination of the floor in a plurality of directions, said releasable means including self-locking linkage winding mechanisms adapted to wind on the shaft and so disposed that the mechanism on one side of the floor winds in the opposite direction to the other side, thereby securing the floor against lateral movement. 75

5. In a dump car, the combination with a door opening extending longitudinally of the car; of a load discharging floor adapted to close the said opening; a series of releasable floor supporting means adapted to engage the said floor adjacent its opposite edges, thereby permitting inclination of the floor in a plurality of directions, said releasable means including floor supporting mechanism disposed at the ends of the floor; 80 and a transverse baffle plate interposed between said supporting mechanism and the end of the floor. 85

6. In a dump car, the combination with a series of longitudinally extending discharge openings in the floor of the car, a transversely extending cross-structure disposed intermediately of said discharge openings; load discharging floors adapted to close the said discharge openings; releasable floor supporting means adapted to engage each of the said floors adjacent their opposite edges, thereby permitting inclination of the respective floors in a plurality of directions; means for operating a series 100 of said floors in unison comprising longitudinal shafts pivotally mounted in the car structure above the plane of the movable floors and extending from one floor to the other; cross-shafts disposed adjacent the ends of the floors for operating the respective floors; and worm and gearing connections between the respective cross-shafts and longitudinal shafts. 105

7. In a dump car, the combination with 110 the center sills and fixed sides and ends of the car; of hoppers on either side of the said center sill and extending intermediately of the trucks of the car; doors for the said hoppers adapted to have two-way movement 115 to discharge the lading either between the rails or outwardly thereof as desired; a load carrying space intermediate the hoppers and the end of the car; and a movable floor member disposed in the aforesaid load carrying space and adapted to be positioned to either direct lading towards the hoppers or to be positioned to form a portion of the car floor. 120

8. In a railway dump car, the combination with the sides of the car and the center sill; of longitudinal hoppers on each side of the car adjacent the center sill, each of said hoppers having its longitudinal walls 125 respectively spaced from said center sill and 130

the corresponding side wall; a door for each of said hoppers, each of said doors having releasable pivots to provide two-way movement for the door; and longitudinally extending operating shafts associated with the hoppers, and disposed above the doors, for operating the said releasable hinge pivots, one of said shafts being disposed intermediate the center sill and the adjacent related hopper wall, and the other of said shafts being disposed intermediate the side wall of the car and the adjacent hopper wall.

9. In a railway car, the combination with a discharge hopper having an opening; and 15 a closure adapted to close the opening; and releasable supporting means adapted to sup-

port the closure adjacent its opposite edges and permit inclination of the said closure in two different directions, said releasable means including a pivotal connection with the closure at a point below the floor level of the closure, said closure also having the outer ends thereof extended beyond the pivotal connection and deflected downwardly to present an extended load shedding surface for said door beyond said pivotal connection.

In witness that I claim the foregoing I have hereunto subscribed my name this 12th day of February 1925.

ARGYLE CAMPBELL.
